UNITED STATES PATENT OFFICE.

BURT W. THAYER, OF MINNEAPOLIS, MINNESOTA.

UNDERGARMENT.

1,393,468.

Specification of Letters Patent. Patented Oct. 11, 1921.

Application filed June 25, 1920. Serial No. 391,669.

To all whom it may concern:

Be it known that I, BURT W. THAYER, a citizen of the United States, resident of Minneapolis, in the county of Hennepin and State of Minnesota, have invented certain new and useful Improvements in Undergarments, of which the following is a specification.

This invention relates to improvements in 10 undergarments which may be in the form of a shirt or a union suit. The garment is particularly designed for the use of children, but may be made of proper size to be worn by adults.

15 The invention consists generally in an undergarment provided with the usual opening from the neck opening down the front, with a sheet or section, preferably of the same material as the body of the garment, arranged so that a portion preferably about one-half thereof extends under one side of the front part of the garment and is permanently secured thereto while the other part projects beyond the vertical central 20 opening and is adapted to lie beneath the other side of the front of the garment and to have its edge secured, preferably by buttons, to the wall of the garment near the side thereof.

25 In the accompanying drawing forming part of the specification,

Figure 1 is a front view of a portion of a union suit, having my improvement applied thereto, the front of the garment being unbuttoned and one side thereof being turned back to expose the sheet or section that is arranged inside of the garment front.

30 Fig. 2 is a similar view showing the overlapping edges of the front of the garment buttoned together, the position of the inside sheet being indicated by dotted lines,

Fig. 3 is a transverse section on line 3—3 of Fig. 2.

35 In the drawings 1 represents the body of the garment, which is here shown as in the form of a union suit, although if preferred the invention may be applied to a separate shirt. This garment opens down the front, being provided with the overlapping edges 2 and 3, one edge—the underlapping—being provided with a series of buttons 4, and the overlapping edge being provided with a corresponding series of buttonholes 5. I provide a sheet or section 6, which is usually

formed of the same material as the body of 55 the garment, and is preferably of oblong shape and adapted to entirely cover the inner portion of the front of the garment, as indicated in Figs. 1 and 2 of the drawings. One edge of this sheet indicated at 7 is permanently secured, preferably by sewing, 60 within the underlapping side or portion of the front of the garment, as shown clearly in Fig. 3 of the drawings. There is also preferably a row of stitching 8 arranged 65 near the edge, or substantially in line with, that carries the row of buttons 4. The sheet 6 extends for substantially half of its width beyond the edge 2 of the garment, as indicated in Fig. 1, so as to be adapted to 70 underlie the other half of the front of the garment, and it is preferably provided with buttons 9 that are adapted to button through the button-holes 10 arranged in the body of the garment near the side thereof, as indicated in the drawing.

75 It will thus be seen that the part of the sheet 6 that is under one-half of the front of the garment is permanently secured to the inside of this part of the garment, while the 80 other half of the sheet projects therefrom and is adapted to underlie the other half of the front of the garment and to be held in place by the buttons 9, on its free edge adapted to engage the button-holes 10. 85 After the garment has been put on by the wearer this portion of the sheet is spread across the body and the buttons 9 are inserted through the button-holes 10 near the side of the body of the garment, and the 90 overlying front portion of the garment is then drawn across this part of the sheet and is buttoned to the other side of the front in the usual way.

95 The garment thus produced is very much warmer than an ordinary garment that buttons down the front, as the overlapping edges of the garment are covered by this inside sheet, and the entire front of the garment is made of double thickness. With 100 slight expense a very much warmer garment is produced and one that has the appearance of an ordinary garment that is arranged to be buttoned down the front.

105 I claim as my invention:

A garment of the class described having a central vertical opening with overlapping edges, and means for securing said edges

together, of an underlying sheet having one portion thereof permanently secured inside of the front portion of the garment at one side of its vertical opening, and the remaining portion of the sheet projecting beyond the vertical opening line of the garment, and provided with means for securing its face

edge to the inside wall of the garment near the side thereof, said single underlying sheet imparting a double thickness to each of the two separable front portions of the garment.

In witness whereof, I have hereunto set my hand this 22nd day of June, 1920.

BURT W. THAYER.
